PACKING DEVICE

Hanns Hornschuch, Easton, Pa., assignor to
 Ingersoll-Rand Company, New York, N. Y., a
 corporation of New Jersey

Application January 7, 1944, Serial No. 517,391

1 Claim. (Cl. 286—27)

This invention relates to packing devices, and more particularly to a packing device for shafts of centrifugal pumps and the like.

One object of the invention is to assure the interception of all such fluid as may leak from the stuffing box of a pump and thereby prevent the splashing of such fluid upon the external parts of the pumping mechanism or upon an attendant operating the pump.

Other objects will be in part obvious and in part pointed out hereinafter.

In the drawing accompanying this specification and in which similar reference numerals refer to similar parts,

Figure 1 is a longitudinal elevation, partly in section, of a centrifugal pump equipped with a packing device constructed in accordance with the practice of the invention.

Figure 2 is an elevation, in section, of the packing compressor.

Figure 3 is a transverse view taken through Figure 2 on the line 3—3, and

Figure 4 is an end view of the packing compressor.

Referring more particularly to the drawing, 20 designates a centrifugal pump of the horizontal type, and 21 a pump casing that is recessed to provide a pumping chamber 23 for the accommodation of an impeller 24 serving to impel liquid from an inlet opening 25 to a discharge opening 26.

The casing 21 is supported by a main frame 27 and secured thereto by bolts 28, and in the main frame is a bearing 29 for a shaft 30 that extends into and is secured to the hub 31 of the impeller 24 by a key 32. A cap screw 33 threaded into the shaft 30 seats against the hub 31 for retaining the impeller upon the shaft and for pressing the hub against an end of a sleeve 34 encircling the shaft and seating at its other end against a shoulder 35 on the shaft.

On the side of the casing 21 adjacent the pumping chamber 23 is a stuffing box 36 that extends into the main frame and in its bore 37 are rings of plastic packing material 38 that encircle the sleeve 34. A lantern 39 is arranged in the intermediate portion of the bore 37, and a conduit 40 is threaded to the stuffing box for supplying sealing liquid to the lantern.

The packing material 38 is compressed by a gland 41 that extends slidably into the outer end of the bore 37, and the gland, constructed in accordance with the practice of the invention, carries means for intercepting such fluid as may leak from the pumping chamber 23 along the surface

of the bore 37 and the sleeve 34 to the atmosphere. To this end the gland 41 is provided with a casing 42 that encircles the gland and has an aperture 43 in one end to receive a tubular terminal portion 44 of the stuffing box 36. The aperture 43 is only sufficiently larger than the peripheral surface of the tubular portion 44 to enable the casing 42 to slide freely axially of the stuffing box. The opposite end wall 45 of the casing 42 is also provided with an aperture 46 to accommodate the sleeve 34 in a like manner.

The gland 41, which is preferably formed integrally with the casing 42, is of annular shape and is joined to the end wall 45 of the casing by a skirt portion 47 and to the side wall of the casing 42 by radially extending ribs 48. The skirt portion 47 is suitably perforated to permit such fluid as may leak along the shaft into the gland to pass into the casing 42. The compressor comprising the gland and the casing 42 is shown as being constructed of two parts 49 and 50 which differ only from each other in that the part 50 is provided with a drain tube 51 for the escape of fluid from the interior 52 of the casing 42.

The casing parts 49 and 50 are firmly clamped together by bolts 53, and on opposed sides of the parts, adjacent the bolts, are lugs 54 that cooperate with each other to define slots 55 for the accommodation of stud bolts 56 threaded into diametrically opposed portions of the stuffing box 36. The lugs 54 also act as seats for nuts 57 threaded on to the bolts 56 to force the gland 41 against the packing material for compressing it.

As a preferred arrangement, the portion of the sleeve 34 lying within the casing 42 is provided with a collar 58 to fling off fluid creeping along the surface of the sleeve and thereby prevent such fluid from continuing along the shaft through the aperture 46 to the exterior of the casing 42.

In operation, the gland 41 is actuated, in the usual manner, for compressing the packing material 38 by manipulating the nuts 57. Being integral with the gland the casing 42 will move with it and will, therefore, always be in position to receive any fluid that may leak out of the stuffing box 36 and will also act as a fender to prevent the splashing of fluid from the shaft into the atmosphere.

In practice, the present invention has been found to be particularly advantageous for use on pumping mechanisms serving to pump chemicals that may cause damage to parts of the pumping mechanism that are not particularly suited to withstand the corrosive action of the fluid. It is,

therefore, necessary to use the comparatively costly corrosion-resisting material for only those parts that must of necessity be exposed to the fluid being pumped.

I claim:

A packing device, comprising a housing having a bore, a tubular extension on the housing forming a continuation of the bore, a shaft in the bore, packing material in the bore to encircle the shaft, a casing having an opening at one end to

receive the end of the tubular extension and having a chamber to receive fluid leaking along the wall of the bore and along the shaft, a gland within the casing for compressing the packing material, and a skirt to connect the gland to the casing and being perforated to permit the passage of fluid from the interior of the gland into the chamber.
